US0D1083094S

(12) **United States Design Patent** (10) **Patent No.:** **US D1,083,094 S**
Blurton et al. (45) **Date of Patent:** **** Jul. 8, 2025**

(54) **PERIANAL SUPPORT DEVICE**(71) Applicant: **STETRIX, INC.**, Bartlett, TN (US)(72) Inventors: **David D. Blurton**, Whiteville, TN (US); **Mark Buchanan**, Atoka, TN (US)(73) Assignee: **Stetrix, Inc.**, Bartlett, TN (US)(***) Term: **15 Years**(21) Appl. No.: **29/852,144**(22) Filed: **Sep. 2, 2022****Related U.S. Application Data**

(63) Continuation of application No. 17/578,951, filed on Jan. 19, 2022, now Pat. No. 11,497,640, which is a continuation of application No. 17/512,244, filed on Oct. 27, 2021.

(51) **LOC (15) Cl.** **24-02**
(52) **U.S. Cl.**USPC **D24/133**
CPC ..... **A61F 5/0093** (2013.01)(58) **Field of Classification Search**USPC D24/104, 112–114, 127–131, 133, 186;
D7/681–686
CPC A61B 17/42; A61F 5/0093; A61M 29/00

CLAIM

The ornamental design for a perianal support device as shown and described.

DESCRIPTION

FIG. 1 is a perspective view of a perianal support device showing our new design; and,

FIG. 2 is another perspective view thereof.
